FIG. III.

FIG. IV.

FIG. V.

Inventor:

DAVID BURDESS FLOWER,

*G. Arthur E. Page,
Attorney.*

UNITED STATES PATENT OFFICE.

DAVID BURDESS FLOWER, OF GLENSIDE, PENNSYLVANIA.

ELECTRIC-BRUSH HOLDER.

Application filed March 11, 1924. Serial No. 698,404.

To all whom it may concern:

Be it known that I, DAVID BURDESS FLOWER, a citizen of the United States, residing at Glenside, in the county of Montgomery and State of Pennsylvania, have invented a certain new and useful Improvement in Electric-Brush Holders, whereof the following is a specification, reference being had to the accompanying drawings.

10 My invention relates to means for adjustably supporting an electrical contact brush in cooperative relation with, and under pressure, upon a rotary contact surface. As hereinafter described; my invention includes a holder which is merely a guide for a brush which is movable therethrough but otherwise independent of said holder; the latter serving merely to precisely determine the position of such a brush. My present invention is of the general class claimed in Letters Patent of the United States 1,319,147 granted to me October 21, 1919, in that it includes a metallic box through which the brush is adjustably pressed toward the contact surface by means of a lever operatively connected with a spring which may be adjusted to vary the spring pressure upon the lever and, consequently, the pressure upon the brush. However, the brush box shown 20 in said Letters Patent is, like other brush boxes of the prior art, formed of cast metal which must be broached or otherwise finished upon the four rectangularly related inner surfaces thereof in relation to which the brush slides through the box. Such boxes are worn at their inner surfaces not only by the normal sliding feed movement of the brushes which are held therein, but also by the vibration of the brushes incident to the 30 operation of the dynamo or motor which is provided with the rotary contact surface aforesaid. When such boxes become even slightly worn; there is a tendency for the electric current to spark at each interstice between the box and the brush and thus erode the surfaces of both and interfere with the normal operation thereof. In holders of the prior art aforesaid, the only remedy for such sparking is to discard the worn box 40 and provide the holder with a new one at considerable cost. Therefore, it is the purpose and effect of my present invention to substitute for the ordinary cast metal brush boxes aforesaid, boxes formed of an assemblage of primarily separate and separable plane metal plates and spacing blocks, all

of which may be formed of ordinary commercial rolled metal stock having surfaces which are smoothly finished by the rolling operation forming such stock sheets and bars. Such construction and arrangement have four distinct advantages, viz, first, such rolled metal is far more resistant to wear than the cast metal aforesaid and is consequently more durable. Second, use of such smoothly finished commercial metal avoids the necessity for the costly broaching operation heretofore required. Third, the boxes may be made to hold brushes of different dimensions, with plates of the same size, by assembling such plates with different sizes of spacing blocks between them. Fourth, the plates and bars forming the box have parallel plane surfaces upon their opposite sides, so that they may be reversed to present the outside unworn surfaces inside when the primarily inside surfaces become worn; so that the durability of each piece of such a box, subject to wear, is thus doubled. As hereinafter described; the separable pieces of such a box are normally held in assembled relation by ordinary cap screws which are prevented from loosening under the vibration to which they are subjected by locking strips of peculiar construction.

My invention includes the various novel features of construction and arrangement hereinafter more definitely specified.

In said drawings: Fig. I is a plan view of a holder embodying my invention.

Fig. II is a side elevation of said holder.

Fig. III is a front elevation of said holder.

Fig. IV is a perspective view of one of the two locking strips shown in Fig. III, but in the form to which it must be bent to release the cap screws which hold the box plates.

Fig. V is a perspective view of one of the reversible box plates shown in Figs. I, II and III.

In said figures; the brush 1, which is a rectangular block, is mounted to reciprocate in a box 2 but is thrust toward the rotary contact surface 3 by the cross heads 4 of the levers 5 which are fulcrumed upon the studs 6 and pressed in the direction of the arrow shown in Fig. II by the coiled wire springs 7 which encircle said studs 6 between the bifurcations 8 of the respective levers. Each of said springs 7 has its outer end 9 engaged with its respective lever and

has its inner end 10 engaged in the slot 12 of the respective stud 6, as indicated in Figs. I and II. Said studs 6 are mounted for rotary adjustment in axially alined bearings 5 13 and 14 of the holder frame 15 and have the circumferential series of conical "spot" sockets 16 for selective engagement with the set screws 18 which are in respective screw threaded engagement with the bearings 13 and have their inner conical ends engaging one of said sockets 16, as indicated in Fig. II. Each of said studs 6 is also provided with a series of openings 20, preferably extending diametrically therethrough, to receive a cross bar by which said studs may be turned to adjust the tension of the respective springs 7 when said set screws 18 are retracted.

Said brush holder frame 15 is provided 20 with the vertically extending clamping flange 22 having the slot 23 for a bolt whereby the entire holder may be detachably adjustably connected with a dynamo or motor provided with said rotary contact 25 surface 3. However, it is to be understood that any other suitable means may be employed to support the holder in the desired position.

I find it convenient to provide said holder 30 15 with sockets 25 upon opposite sides thereof, each having a pair of set screws 26 to clamp an electric conductor whereby current is supplied to said holder 15 and thence to said brush 1. Moreover, I prefer to provide each of said levers 5 with a flexible conductor 28 which is rigidly connected therewith by the rivet 29 at one end; the opposite ends of said conductors 28 being respectively connected with said holder frame 40 15 by screws 30.

As shown; said holder 15 has a flange 31 with a plane face 32 to which said box 2 is secured by four cap screws 34 which are locked in the assembled position shown by the metal locking strips 35 which are primarily flat but which are upturned at their ends as indicated in Fig. IV, and thereafter bent around the heads of said screws 34 as indicated in Figs. I, II and III.

50 As shown, said box 2 is formed of two opposite plates 37 which are precisely alike and of the configuration shown in Figs. III and V, so that they may be reversed to present either of their opposite plane faces toward said brush 1. Said plates 37 are separated in any desired spaced relation corresponding with the thickness of the brush 1, by the spacing blocks 38 which may be of different interchangeable sizes corresponding 60 with the different thicknesses of such brushes 1.

It is to be understood that when the box 65 shown becomes worn upon its inner surfaces; said locking strips 35 may be bent out at their ends to release the heads of said

screws 34 and the latter withdrawn from their threaded engagement with said flange 31 on the holder frame 15 to release said box plates 37 which may then be reversed, replaced and secured by said cap screws 34 70 which may be again locked against accidental rotation by rebending the ends of said locking strips 35 to the position shown.

Of course, such holders are made of different sizes and shapes as required by the 75 dimensions of the electric machines to which they are to be attached. In fact, I am manufacturing about two hundred different forms of holders within the description of the claims of my Letters Patent 1,319,147. 80

Therefore, I do not desire to limit myself to the precise details of construction and arrangement herein set forth, as it is obvious that various modifications may be made therein without departing from the 85 essential features of my invention, as defined in the appended claims.

I claim:

1. In an electric brush holder; the combination with a frame having a flange with a plane face for engagement with a brush box; said flange having two pairs of screw threaded sockets at respectively opposite ends thereof; a brush box formed of two similar parallel plane faced sheet metal plates, which are symmetrical and reversible to present either of their plane faces toward the brush; said plates being separated, in parallel spaced relation, by spacing blocks; said plates and spacing blocks having pairs of holes therethrough registering with the screw sockets in said flange; sheet metal locking strips each having a pair of holes registering with the respective pairs of said screw sockets; two pairs of cap screws 90 extending through said plates and spacing blocks in screw threaded engagement with said sockets and having heads resting upon said locking strips; the ends of said strips being so bent in engagement with the heads of said screws as to normally prevent rotation of the latter from assembled position; whereby a rectangular smooth faced slide bearing for a brush is afforded between said plates and blocks; a brush slidably fitted in said box; three axially alined stud bearings in said frame, two at respectively opposite sides thereof and one intermediate of the width of said frame; two cylindrical studs mounted in said bearings, the inner ends of both studs being journaled in said intermediate bearing; each of said studs having a longitudinal slot, a circumferential series of spot sockets, and a wrench hold at one end thereof; set screws in said outer stud bearing arranged to selectively engage said sockets; two levers each having bifurcations extending between said intermediate bearing and the respective outer bearings and journaled upon said stud and arranged to 100 105 110 115 120 125 130

press the brush; coiled springs respectively encircling said studs between the bifurcations of the respective levers; each spring having one end engaging its lever and having the other end engaging the slot in its stud.

2. In an electric brush holder; the combination with a frame having a plane face for engagement with a brush box, with two pairs of screw threaded sockets at respectively opposite ends thereof; a brush box formed of two similar parallel plane faced sheet metal plates, which are symmetrical and reversible to present either of their plane faces toward the brush; said plates being separated, in parallel spaced relation, by spacing blocks; said plates and spacing blocks having pairs of holes therethrough registering with said screw sockets; sheet metal locking strips each having a pair of holes registering with the respective pairs of said screw sockets; two pairs of screws extending through said plates and spacing blocks in screw threaded engagement with said sockets and having heads resting upon said locking strips; the ends of said strips being so bent in engagement with the heads of said screws as to normally prevent rotation of the latter from assembled position; whereby a smooth faced slide bearing for a brush is afforded between said plates and blocks; a brush slidably fitted in said box; axially alined stud bearings in said frame; a cylindrical stud mounted in said bearings, said stud having a longitudinal slot, and a circumferential series of spot sockets; a set screw arranged to selectively engage said sockets; a lever having bifurcations extending between said bearings and journaled upon said stud and arranged to press the brush; and a coiled spring encircling said stud between the bifurcations of said lever; said spring having one end engaging its lever and having the other end engaging the slot in its stud.

3. In an electric brush holder; the combination with a frame having a face for engagement with a brush box, with two pairs of screw threaded sockets at respectively opposite ends thereof; of a brush box formed of two similar parallel plane faced sheet metal plates, which are symmetrical and reversible to present either of their plane faces toward the brush; said plates being separated, in parallel spaced relation, by spacing blocks; said plates and spacing blocks having pairs of holes therethrough registering with the screw sockets in said flange; sheet metal locking strips each having a pair of holes registering with the respective pairs of said screw sockets; two pairs of cap screws extending through said plates and spacing blocks in screw threaded engagement with said sockets and having heads resting upon said locking strips; the ends of said strips being so bent in engagement with the heads of said screws as to normally prevent rotation of the latter from assembled position; whereby a smooth faced slide bearing for a brush is afforded between said plates and blocks; a brush slidably fitted in said box; axially alined stud bearings in said frame; a cylindrical stud mounted in said bearings, said stud having a longitudinal slot, and a circumferential series of spot sockets; a set screw arranged to selectively engage said sockets; a lever having bifurcations extending between said intermediate bearing and the respective outer bearings and journaled upon said stud and arranged to press the brush; coiled springs respectively encircling said studs between the bifurcations of the respective levers; each spring having one end engaging its lever and having the other end engaging the slot in its stud.

4. In an electric brush holder; the combination with a frame having a face for engagement with a brush box, with two pairs of screw threaded sockets at respectively opposite ends thereof; a brush box formed of two similar parallel plane faced sheet metal plates, which are reversible to present either of their plane faces toward the brush; said plates being separated, in parallel spaced relation, by spacing blocks; said plates and spacing blocks having pairs of holes therethrough registering with said screw sockets; sheet metal locking strips

each having a pair of holes registering with the respective pairs of said screw sockets; two pairs of screws extending through said plates and spacing blocks in screw threaded engagement with said sockets and having heads resting upon said locking strips; the ends of said strips being so bent in engagement with the heads of said screws as to normally prevent rotation of the latter from assembled position; whereby a smooth faced slide bearing for a brush is afforded between said plates and blocks; a brush slidably fitted in said box; axially alined stud bearings in said frame; a cylindrical stud mounted in said bearings, said stud having a longitudinal slot, and a circumferential series of spot sockets; a set screw arranged to selectively engage said sockets; a lever having bifurcations extending between said bearings and journaled upon said stud and arranged to press the brush; and a coiled spring encircling said stud between the bifurcations of said lever; said spring having one end engaging its lever and having the other end engaging the slot in its stud.

5. In an electric brush holder; the combination with a frame having a face for engagement with a brush box, with two pairs of screw threaded sockets at respectively opposite ends thereof; of a brush box formed of two similar parallel plane faced sheet metal plates, which are symmetrical and reversible to present either of their plane faces toward the brush; said plates being separated, in parallel spaced relation, by spacing blocks; said plates and spacing blocks having pairs of holes therethrough registering with the screw sockets in said flange; sheet metal locking strips each having a pair of holes registering with the respective pairs of said screw sockets; two pairs of cap screws extending through said plates and spacing blocks in screw threaded engagement with said sockets and having heads resting upon said locking strips; the ends of said strips being so bent in engagement with the heads of said screws as to normally prevent rotation of the latter from assembled position; whereby a smooth faced slide bearing for a brush is afforded between said plates and blocks; a brush slidably fitted in said box; axially alined stud bearings in said frame; a stud mounted in said bearings, said stud having a longitudinal slot, and a circumferential series of spot sockets; a set screw arranged to selectively engage said sockets; a lever having bifurcations extending between said intermediate bearing and the respective outer bearings and journaled upon said stud and arranged to press the brush; and a coiled spring encircling said stud and pressing said lever.

6. In an electric brush holder; the combination with a frame having a face for engagement with a brush box and screw threaded sockets; of a brush box formed of two parallel plane faced sheet metal plates, which are reversible to present either of their plane faces toward the brush; said

- plates being separated, in parallel spaced relation, by spacing blocks; said plates and spacing blocks having holes therethrough registering with said screw sockets; screws 5 extending through said plates and spacing blocks in screw threaded engagement with said sockets; means normally preventing rotation of said screws from assembled position; whereby a smooth faced slide bearing 10 for a brush is afforded between said plates and blocks; a brush slidably fitted in said box; and a spring pressed lever, journaled in said frame and arranged to press said brush.
- 15 6. In an electric brush holder; the combination with a frame having a face for engagement with a brush box and screw threaded sockets; of a brush box including parallel plane faced sheet metal plates, 20 which are reversible to present either of their plane faces toward the brush; spacing blocks separating said plates in parallel relation; said plates and spacing blocks having holes therethrough registering with said 25 screw sockets; screws extending through said plates and spacing blocks in engagement with said sockets; means normally preventing rotation of said screws from assembled position; whereby a smooth faced 30 slide bearing for a brush is afforded between said plates and blocks; a brush slidably fitted in said box; and means arranged to press the brush to operative position.
- 35 7. In an electric brush holder, the combination with a frame having a face for engagement with a brush box and screw threaded sockets; of a brush box including parallel plane faced sheet metal plates, which 40 are reversible to present either of their plane faces toward the brush; spacing blocks separating said plates in parallel relation; said plates and spacing blocks having holes there- 45 through registering with said screw sockets; screws extending through said plates and spacing blocks in engagement with said sockets; means normally preventing rotation of said screws from assembled position; whereby a smooth faced slide bearing 50 for a brush is afforded between said plates and blocks; and means arranged to press the brush to operative position.
- 55 8. In an electric brush holder, the combination with a frame having a face for engagement with a brush box and screw threaded sockets; of a brush box including parallel plane faced sheet metal plates,
- which are reversible to present either of their plane faces toward the brush; spacing blocks separating said plates in parallel relation; said plates and spacing blocks having holes therethrough registering with said screw sockets; screws extending through said plates and spacing blocks in engagement with said sockets; whereby a smooth faced slide bearing 60 for a brush is afforded between said plates and blocks; and means arranged to press the brush to operative position.
- 65 9. In an electric brush holder, the combination with a frame; of a brush box including two similar parallel plane faced sheet metal plates which are symmetrical and reversible to present either of their plane faces toward the brush; rectangular spacing blocks between said plates; and screws, extending through said plates and blocks, 70 detachably connecting them with said frame.
- 75 10. In an electric brush holder, the combination with a frame; of a brush box including two parallel plane faced sheet metal plates, reversible to present either of their plane faces toward the brush; spacing blocks between said plates; and screws extending through said plates and blocks, detachably connecting them with said frame; and locking strips, each common to two of said 80 screws, and arranged to normally prevent rotation of said screws.
- 85 11. In an electric brush holder, the combination with a frame; of a brush box including two parallel plane faced sheet metal plates, reversible to present either of their plane faces toward the brush; spacing blocks between said plates; and screws extending through said plates and blocks, detachably connecting them with said frame; and means 90 arranged to normally prevent rotation of said screws.
- 95 12. In an electric brush holder, a brush box including two parallel plane faced sheet metal plates, reversible to present either of their plane faces toward the brush; spacing blocks between said plates; and screws extending through said plates and blocks, detachably connecting them.

In testimony whereof, I have hereunto signed my name at Philadelphia, Pennsylvania, this 7th day of March, 1924.

DAVID BURDESS FLOWER.
